UNITED STATES PATENT OFFICE.

WILLIAM L. JOHNSON, OF BOSTON, MASSACHUSETTS.

DESIGN FOR A TEETHING-CRACKER.

SPECIFICATION forming part of Design No. 21,337, dated February 9, 1892.

Application filed November 5, 1891. Serial No. 411,003. Term of patent 14 years.

To all whom it may concern:

Be it known that I, WILLIAM L. JOHNSON, a citizen of the United States, residing in Boston, in the county of Suffolk and State of Massachusetts, have invented a new and original Design for a Teething-Cracker, of which the following is a specification, reference being had to the accompanying drawings, forming part thereof.

Figure 1 is a plan or top view of a teething-cracker embodying my design. Fig. 2 is an under side view of same; and Fig. 3 is a transverse section taken on the line of $x x$ of Fig. 1, these three views being deemed necessary to fully illustrate my design.

The leading feature of my design consists of a cracker circular in its general contour and

having a circular hole through its center, the upper or top surface being a beaded fillet.

A represents the cracker; B, the hole in the center of the same; D, the outer bead; E, the fillet, and F the inner bead. The bottom G is flat, with the corners $g g'$ rounded off, and both the outer side H and the inner side I are rounded inwardly up to the beads D and F at the top of the cracker.

What I claim is—

The design for a teething-cracker, as herein shown and described.

WILLIAM L. JOHNSON.
